UNITED STATES PATENT OFFICE.

CHARLES W. HOWARD, OF GREENWICH, CONNECTICUT, ASSIGNOR TO CONSOLIDATED TEXTILE CORPORATION, OF NEW YORK, N. Y., A CORPORATION OF DELAWARE.

DESIGN FOR A TEXTILE FABRIC.

Application filed May 2, 1923. Serial No. 6,033. Term of patent 7 years.

To all whom it may concern:

Be it known that I, CHARLES W. HOWARD, a citizen of the United States, and a resident of Greenwich, in the county of Fairfield and State of Connecticut, have invented a new, original, and ornamental Design for Textile Fabrics, of which the following is a specification, reference being had to the accompanying drawing, forming a part hereof.

The drawing illustrates a section of textile fabric embodying my design.

The design is characterized by a combination of smooth and roughened finished surfaces, the latter being produced by crinkling

or creping, and the surfaces are disposed in the fabric so as to provide a checkered appearance in which the plain or smooth finished portions alternate with those having the roughened finish, the plain or smooth finished portions being embellished with the representation of a bird on a twig or branch.

I claim:

The ornamental design for a textile fabric, substantially as shown and described.

CHARLES W. HOWARD.

Witnesses:

HENRY B. STIMSON,
P. FRANK LOMACH.
